A detailed technical line drawing of a double-bladed scroll saw. The saw is shown from a top-down perspective, with its two blades extending downwards. The internal frame and various mechanical parts are visible. Labels A through Z are placed around the saw to identify specific components: A is at the top left, B is at the top center, C is on the left side, D is at the top right, E is on the right side, F is at the bottom center, G is on the left side, H is at the bottom left, I is at the bottom right, J is on the right side, K is at the bottom center, L is on the left side, M is at the top center, N is on the right side, O is on the left side, P is at the top center, Q is on the right side, R is at the bottom center, S is on the left side, T is at the bottom right, U is on the right side, V is at the bottom center, W is on the left side, X is at the top center, Y is on the right side, and Z is at the bottom center.

ATTORNEYS

UNITED STATES PATENT OFFICE.

HENRY T. SMITH, OF CARROLL, OHIO.

SASH-FASTENER.

SPECIFICATION forming part of Letters Patent No. 425,191, dated April 8, 1890.

Application filed February 1, 1890. Serial No. 338,934. (No model.)

To all whom it may concern:

Be it known that I, HENRY T. SMITH, residing at Carroll, Fairfield county, and State of Ohio, have invented a new and improved 5 Sash-Lock, of which the following is a specification.

My invention is an improvement in sash-fasteners; and the invention consists in certain novel constructions and combinations of 10 parts, as will be hereinafter described and claimed.

In the drawings, Figure 1 is a front view of a window provided with my improvement, parts being broken away. Fig. 2 is a horizontal section. Fig. 3 is a face view of one 15 side of the window-frame provided with my improved fastener. Fig. 4 is a view of a part of one edge of one of the sashes. Fig. 5 is a perspective view of the fastener, and Figs. 6 20 and 7 are detail views.

The fastener proper consists of a case A, formed with parallel wings B B', and a connecting-wing C, which unites the wings B B', the whole case presenting an approximately 25 Z-shape, as shown. The wings B B' are made hollow and are closed on their inner sides or backs by a cover-plate a, which, preferably, is pivoted to the case so it may be turned clear of the interior of wings B B' when access thereto is desired. Longitudinal slots b 30 are formed in the faces of wings B B', and openings b' are formed in the ends of such wings for the passage of the handle-rods D, D, which extend through such openings b' and are threaded on their inner ends. The lock-blocks E are held and slide within the 35 wings B B', and are provided with threaded sockets to receive the ends of the handle-rods, which are turned thereinto, as shown. The 40 actuating-springs F are fitted on the rods D and bear between the latch-blocks and the end wall of the casing. These latch-blocks are formed or provided with bolt-like portions e, which extend through slots b and pro-

ject sufficiently far to enter the notches or 45 seats in the sash-frames. The sash-frames G have in their edges grooves g, in the outer walls of which are formed notches or seats to receive the bolts e, such notches being arranged correspondingly to the positions in 50 which it is desired to hold the sashes, and the bolt e when in such notches operating to lock the sash firmly in position.

In applying the fastening, the case A, with the handle-rods removed, is fitted in a suitable mortise-frame in the window-frame, as shown, and the handle-rods are passed through suitable holes in the sash through 55 openings b' and into the wings B B', and are threaded to the lock-blocks, the said handle-rods thus serving to retain the casing A in 60 place.

The device is simple, easily operated, and by it either sash may be held in any suitable 65 adjustment.

Having thus described my invention, what I claim as new, and desire to secure by Letters Patent, is—

The improved sash-lock, consisting of the casing having the parallel wings, and the 70 connecting wing uniting the inner ends thereof, having in the front face of such parallel wings longitudinal slots and in the ends of such wings perforations or openings, the lock-blocks held and adapted to slide in said parallel wings and provided with bolt-like portions extended through the face-slots, the 75 handle-rods passed through the openings in the ends of the case-wings and connected with the lock-blocks, and the springs on said 80 rods arranged to bear between the lock-blocks and the ends of the casing, all substantially as and for the purpose set forth.

HENRY T. SMITH.
